(57) **CLAIM**

The ornamental design for a gate frame member, as shown and described.

DESCRIPTION

FIG. 1 is a top elevational view showing our new design for a gate frame member;

FIG. 2 is a bottom plan view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view showing a second embodiment of the gate frame member;

FIG. 8 is a bottom plan view thereof, the right and left sides being identical to the right and left sides shown in FIGS. 3 and 4;

FIG. 9 is a front elevational view thereof;

FIG. 10 is a rear elevational view thereof;

FIG. 11 is a top plan view showing a third embodiment of the gate frame member. The right and left sides being identical to the right and left sides shown in FIGS. 3 and 4, and the bottom being identical to the bottom shown in FIG. 8;

FIG. 12 is a front elevational view thereof;

FIG. 13 is a rear elevational view thereof;

FIG. 14 is a top plan view of a fourth embodiment of the gate frame member. The right and left sides being identical to the right and left sides shown in FIGS. 3 and 4, and the bottom being identical to the bottom shown in FIG. 8;

FIG. 15 is a front elevational view thereof; and,

FIG. 16 is a rear elevational view thereof.
